BRASSIÈRE

Gabrielle M. P. Yerkes, Hartsdale, N. Y., assignor
to G. M. Poix, Inc., New York, N. Y., a corpora-
tion of New York

Application November 18, 1937, Serial No. 175,222

6 Claims. (Cl. 2—42)

The object of this invention is to provide a brassière in which novel means are employed to exert a converging upward pull on the breasts of the wearer, this being accomplished by yielding 5 supporting the right breast from the left shoulder and the left breast from the right shoulder; means being employed to adjust accurately this yielding converging upward pull on the breasts.

10 A practical embodiment of this invention is represented in the accompanying drawing, in which

Fig. 1 represents a front view of the brassière as in use;
15 Fig. 2 represents a back view of the same; and
Fig. 3 represents a detail section on an enlarged scale along one of the shoulder straps, taken in the plane of the line III—III of Fig. 1.
The brassière comprises two breast portions 1 and 2, generally oval in contour and permanently connected at the front of the brassière. These two breast portions respectively terminate in tapered side portions 3 and 4 which extend partly across the back of the wearer. The ends 20 of these tapered side portions are provided with elastic straps 5 and 6, adapted to be removably connected, as, for instance, by providing the free end of one strap with a hook 7, and the free end of the other strap with a loop 8, adapted to receive the said hook.

Left and right adjustable shoulder straps 9 and 10 lead respectively upward from the ends of the tapered side portions 3 and 4 at the back of the brassière over the left and right shoulders of the wearer, thence diagonally downward and inward in sliding engagement with the tops of their corresponding fulled breast portions, as, for instance, through adjacent slits 11 and 12 respectively, and from thence across each other into 35 the bottom hem 13 and 14 respectively of their opposite breast portions, the left shoulder strap 9 extending a distance along within the right bottom hem 14, and the right shoulder strap 10 extending a distance along within the left bottom hem 13. The lower front ends of these shoulder straps are provided with elastic portions 15 and 16 respectively, located and freely extensible within the bottom hem 13 and 14, to allow the shoulder straps to yield somewhat under strain. 40 The remaining portions of the shoulder straps are preferably of inelastic material. The free ends of the elastic portions 15 and 16 of the shoulder straps are suitably anchored within their respective bottom hem, to permit the yielding 45 of the shoulder straps as above described.

The adjustability of the shoulder straps may be accomplished by providing sliding buckles 17 and 18 and eyes 19 and 20, through which eyes the hook portions 21 and 22 of the shoulder straps pass.

To ensure the proper positioning of the brassière, supplementary straps 23 and 24 extend, respectively, from the top hem 25 and 26 of the breast portions upwardly to the shoulder straps 9 and 10, preferably at points above the means for adjusting the shoulder straps. These supplementary straps are preferably made of inelastic material.

From the above description it will be seen that both shoulder straps may be accurately adjusted so that a yielding converging upward pull on the breasts of the wearer is accomplished.

It is evident that various changes may be resorted to in the construction, form and arrangement of the several parts without departing from the spirit and scope of my invention, and hence I do not intend to be limited to the particular embodiment herein shown and described, but

What I claim is:

1. A brassière comprising breast portions permanently connected at the front of the brassière and terminating in tapered side portions, means for removably connecting the side portions at the back of the wearer, and shoulder straps extending upwardly from the ends of the side portions over the shoulders, thence diagonally downward and inward in sliding engagements with the tops of their corresponding breast portions and from thence freely across each other within the brassière and anchored to the bottoms of their opposite breast portions.

2. A brassière comprising breast portions permanently connected at the front of the brassière and terminating in tapered side portions, means for removably connecting the side portions at the back of the wearer, and shoulder straps extending upwardly from the ends of the side portions over the shoulders, thence diagonally downward and inward in sliding engagements with the tops of their corresponding breast portions and from thence freely across each other within the brassière and anchored to the bottoms of their opposite breast portions, and supplementary straps leading upwardly from the tops of the breast portions to the shoulder straps.

3. A brassière comprising breast portions permanently connected at the front of the brassière and terminating in tapered side portions and having top and bottom hem, means for removably connecting the side portions at the back of

the wearer, the tops of the said breast portions having adjacent slits therethrough, shoulder straps extending upwardly from the ends of the side portions over the shoulders, thence diagonally downward and inward through said slits in their corresponding breast portions and from thence 5 downward and inward through said slits in their corresponding breast portions and from thence freely across each other within the brassière into the bottom hems of their opposite breast portions and there anchored.

10 4. A brassière comprising breast portions terminating in tapered side portions and having top and bottom hems, means for removably connecting the side portions at the back of the wearer, the tops of the said breast portions having adjacent slits therethrough, shoulder straps extending 15 upwardly from the ends of the side portions over the shoulders, thence diagonally downward and inward through said slits in their corresponding breast portions and from thence across each other into the bottom hems of their opposite breast portions and there anchored, said shoulder straps having elastic portions freely extensible within said bottom hems.

15 5. A brassière comprising breast portions terminating in tapered side portions and having top and bottom hems, means for removably connecting the side portions at the back of the wearer, the tops of the said breast portions having adjacent slits therethrough, shoulder straps extending 20 upwardly from the ends of the side portions over the shoulders, thence diagonally downward and inward through said slits in their corresponding breast portions and from thence across each other into the bottom hems of their opposite breast portions and there anchored, said shoulder straps having elastic portions freely extensible within said bottom hems, means for adjusting the lengths of the shoulder straps, and supplementary straps leading upwardly from the top 25 hems of the breast portions to the shoulder straps.

extending upwardly from the ends of the side portions over the shoulders, thence diagonally downward and inward through said slits in their corresponding breast portions and from thence across each other into the bottom hems of their opposite breast portions and there anchored, said shoulder straps having elastic portions freely extensible within said bottom hems, and means for adjusting the lengths of the shoulder straps.

6. A brassière comprising breast portions terminating in tapered side portions and having top and bottom hems, means for removably connecting the side portions at the back of the wearer, the tops of the said breast portions having adjacent slits therethrough, shoulder straps extending 10 upwardly from the ends of the side portions over the shoulders, thence diagonally downward and inward through said slits in their corresponding breast portions and from thence across each other into the bottom hems of their opposite 15 breast portions and there anchored, said shoulder straps having elastic portions freely extensible within said bottom hems, means for adjusting the lengths of the shoulder straps, and supplementary straps leading upwardly from the top 20 hems of the breast portions to the shoulder straps.

GABRIELLE M. P. YERKES.
